UNITED STATES PATENT OFFICE.

AUGUSTINE SHELBOURNE, OF SOUTH PASADENA, CALIFORNIA.

PRESSURE PAINT CONTAINER.

Application filed May 10, 1923. Serial No. 637,959.

Although my present invention may be referred to as a pressure paint container, it should be understood that this invention comprises broadly novel means and methods for the delivery of liquids to and through air brushes, or the like, such as are used in the application of paints, varnishes, enamels, or other liquid coating compositions, hereinafter generally referred to as paints.

5 It is an object of this invention to provide auxiliary means for the delivery of paints to an air brush, or the like in such manner as to employ compressed air not only for an aspirating effect upon the liquid referred to, 10 by a reduction of pressure but also for the production of a positive pressure tending to facilitate the delivery of the liquid to the air brush, or its equivalent.

15 It is a further object of this invention to provide and employ for the purpose referred to means comprising an outer pressure receptacle, which may be structurally similar to a small autoclave or pressure cooker, for confining a body of paint or other liquid to be delivered through a pipe or tube, such as a tube 20 leading to an air brush, and I prefer to employ, in this connection not only a pressure receptacle but also an inner container, such as a paint or varnish can or pail or keg, adapted 25 to confine the coating liquid without necessarily permitting the same to contaminate or come in contact with the walls of the pressure receptacle.

It is a further object of the present invention to provide means permitting a source of high-pressure compressed air to be so employed as to maintain a desired lower pressure within a closed receptacle; and, in a preferred employment of my invention the 30 same source of compressed air may be employed at the mentioned higher pressure to produce an aspirating or air brush effect; and my closed receptacle may optionally be provided also with a gauge or gauges and 35 with a pop valve and a pressure release valve or other means for limiting the pressure therein, as well as suitable means for cutting off at will or under predetermined conditions the flow of air thereto or therefrom, and optionally also with an additional valve to prevent a 40 movement of the coating liquid through the air inlet pipe.

Other objects of my invention will appear 45 from the following description of alternative embodiments thereof, and from the appended

claims taken in connection with the accompanying drawings, in which—

Figure 1 is a top plan view of one embodiment of my invention.

Fig. 2 is a vertical section on the line 2—2 of Fig. 1.

Fig. 3 is a vertical section of an alternative and improved form.

Fig. 4 is a detailed view, on an enlarged scale, which may be regarded as taken on the line 4—4 of Fig. 3.

Referring to the details of that embodiment of my invention shown in Figs. 1 and 2, 1 is an outer pressure receptacle shown as provided with a tight closure 2, extending over the entire top thereof, and provided with a gasket 3, secured in the ring 4 of said closure, and adapted to effect an air-tight joint when the said closure is secured in place by means such as the wing nuts 5, threaded upon the pivoted blots 6, and cooperating with the slotted ears 7 upon said closure, in a well known manner.

Although I might put paint or another coating liquid directly into the mentioned receptacle 1, I prefer to employ therein an independent inner container 8, which may be an ordinary paint pail or varnish can in which the coating composition may have been purchased, this inner container being suitable to retain the liquid coating composition out of contact with the walls of the pressure receptacle proper, although it need not be capable of withstanding high pressure.

Suitably connected with the closure 2, I find it advantageous to employ a plurality of fittings, the most important of which is the exit tube 9, shown as extending approximately to the bottom of the inner receptacle 8 and as externally connected, by means of the coupling 10, elbow 11, and flexible tubing 12, with the paint inlet 13 of the air brush 14, the exit tube 9 thus serving to facilitate the delivery of the paint or other coating composition confined within the inner receptacle 8, when air or another pressure fluid is introduced above the surface thereof, as by means of the inlet 15.

Although any suitable means may be employed for the introduction of air or other pressure fluid through the opening 15, I find it advantageous to use for this purpose a pressure reducing valve 16 of well known type, this pressure valve being shown as provided with a needle controlled by the handle 17, and as connected with a lateral opening 119

18 in a T 19, comprised within the high pressure air supply 20, leaving by means of the flexible extension 21, to the air inlet 22, of the mentioned air brush 14, which may be 5 of any usual or preferred type.

It will be understood that by a suitable adjustment of the pressure reducing valve 16, the flow of air into the interior of the receptacle 1 may be suitably regulated; but I 10 prefer to associate therewith pressure limiting means such as the pop valve 23; and I find it convenient to employ also a gauge 24, in order that the pressure may be conveniently observed at any time and necessary 15 adjustments made in accordance therewith.

In order to release the pressure within the receptacle 1, as when a job has been finished or a new can of paint is to be introduced, I find it convenient to employ also a pressure release valve 25, it being understood that the auxiliary devices last referred to may optionally be connected with a lateral wall of the receptacle 1, or otherwise disposed as may be convenient.

25 In another form of my invention shown in Fig. 3, it will be understood that 1^a is an outer pressure receptacle, which may be of the same general character as that disclosed in Figs. 1 and 2, except that its cover 2^a is 30 preferably fitted not only with an exit tube 9^a, extending into paint or the like, confined within the inner receptacle 8^a, but is also provided with an air inlet pipe 26, extending therein and substantially to the bottom thereof, in order that the air which is to produce a moderate and substantially constant excess pressure above the surface of the mentioned liquid is also effective in the agitation thereof.

40 To support the air inlet pipe 26 I prefer to provide a housing 27, which may be integral with the cover 2^a, and may be provided with a threaded opening 28 adapted to receive the valve seat 29 of a return-preventing or 45 pressure determining automatic valve 30, whose stem 31 is shown as surrounded by a compression spring 32, and confined between an abutment 33 and a washer 34 retained by a nut 35, this nut being adjustable to vary 50 the compression of the mentioned spring. Instead of securing the inlet pipe 26 directly to the housing 27, I find it advantageous to employ a reducing coupling 36, having a threaded engagement with both the pipe 26 55 and the valve seat 29, the construction being such that, when desired, the pipe 26 and all of the mentioned parts associated therewith may be removed together from the housing 27.

60 In the construction now referred to, 19^a being a T whose stem may form an integral lateral connection with the inlet fitting 37, provided with a needle hand valve 38, it will be understood that air admitted from a high-pressure air supply through the lateral passage 39, and past the mentioned needle valve

38, may unseat the valve 30, and pass downward through the inlet pipe 26, bubbling up through the liquid contained in the receptacle 8^a, and producing a desired pressure upon the surface thereof, this pressure being predetermined either by the adjustment of the valve 30 or by the adjustment of a pop valve 23^a, seated in an opening 40, which extends into the interior of the housing 27, it being understood that the needle valve 38 may be 70 so adjusted that the introduction of air in the manner described corresponds approximately to the delivery of paint from my container, in order to avoid an undue waste of air through the pop valve 23^a.

80 A pressure gauge 24^a and a pressure release valve 25^a may advantageously be provided, and it will be understood that the exit tube 9^a may be secured in any preferred manner, as by the coupling nut 41, so that paint will be 85 forced through tube 12^a, connected with an air brush or the like, with which a high-pressure air supply is also connected in the manner shown in Fig. 1, or in any other desired manner, a substantially uniform moderate positive pressure being ordinarily advantageous.

90 Although a pressure container such as I have described above may be made of any suitable material such as aluminum, and of 95 any suitable size, and may obviously be associated with heating means, if desired, I find it advantageous to render my container portable by means of a handle 42, and to adapt the same to receive receptacles of moderate 100 size, such as gallon cans, it being understood, however, that even a very small pail or can may be used in a large receptacle without loss or inconvenience.

105 As is well known to workers in this art, an ordinary air brush, although adapted to produce a slightly negative pressure within a tube with which it may be connected, will lift a coating or other viscous liquid through only a relatively small vertical distance; but, by 110 the employment of my pressure container, compressed air may be employed, at a gauge pressure of say two or three pounds, to force a liquid from a lower level, such as the level of a floor upon which the container may rest, to a higher level, as may be necessary when an air brush is employed in painting or coating, for example, the ceiling of a room, air at 115 a higher pressure from the same main with which my container is connected being then employed as desired, to assist in the delivery of the paint through and from the air brush.

120 Although I have described above two complete, advantageous embodiments of my invention, it will be understood that various parts thereof may be independently used and also that various modifications may be made without a departure from the spirit and scope 125 of my invention, as the same is indicated above and in the following claims.

What I claim is:

1. pressure paint container comprising in combination an outer pressure receptacle having a cover to make an air tight joint therewith, an air tight housing extending 20 downwardly from the cover, an air inlet having a valve in the cover opening into said housing, the housing having a valve seat, a valve slidably mounted therein having a stem, an abutment through which the stem operates, 25 a spring on the stem operatively connected between the abutment and the stem, an air pipe extending downwardly from the housing, and a paint outlet pipe extending through the cover to the base of the container. 30
  - 10
  - 15
  - 20
  - 25
  - 30
- In testimony whereof I have signed my name to this specification.

2. A pressure paint container comprising

A. SHELBOURNE.
